UNITED STATES PATENT OFFICE.

CHARLES H. LINDENBERG, OF COLUMBUS, OHIO.

DESIGN FOR A SWORD-SCABBARD.

SPECIFICATION forming part of Design No. 23,819, dated November 27, 1894.

Application filed October 5, 1894. Serial No. 525,041. Term of patent 7 years.

To all whom it may concern:

Be it known that I, CHARLES H. LINDENBERG, a citizen of the United States, residing at Columbus, in the county of Franklin and state of Ohio, have invented and produced a certain new and original Design for Sword-Scabbards, of which the following is a specification, reference being had to the accompanying drawings hereto annexed and forming part thereof.

Figure 1 is a face view of a section of a scabbard having my design thereon and Fig. 2 is a transverse section on dotted line $x-x$ of Fig. 1—these two views being deemed necessary to fully illustrate my design.

The leading features of my design consist of the raised representation of a cuirass or coat of mail upon the outer face of a scabbard; a passion cross in relief on said coat of mail and mailed hands projecting laterally, said hands grasping the belt strap rings.

a represents the scabbard or front face thereof and b the cuirass which is secured thereto or otherwise raised therefrom, the shoulders of said cuirass projecting slightly past the sides of the scabbard. From these

shoulder portions extend outward at opposite points, representations of mailed hands c which grasp the usual sword belt rings c' . Upon the front of the cuirass is formed as shown, a passion cross b' which may be colored if desired. Rising from the passion cross and extending upward through the neck of the armor b are the head portions of two inclined halberds d . These halberds are surmounted by a plumed helmet indicated at e . Below the bottom fringe f of the armor b is formed a scroll design g from which depends a templar cross h . All of the parts herein shown and described are elevated from or are in relief upon the scabbard body, while the passion cross as more clearly indicated in Fig. 2 of the drawings, is formed in relief upon the coat of mail.

What I claim is—

The design for a sword scabbard, substantially as herein shown and described.

45

CHARLES H. LINDENBERG.

In presence of—

C. M. VOORHEES,
C. C. SHEPHERD.
